TREATMENT OF PSORIASIS

Joseph Glasser, 8801 Shore Road, Brooklyn, N.Y.
No Drawing. Filed Feb. 4, 1960, Ser. No. 6,632
7 Claims. (Cl. 167—65)

This invention relates to therapeutic compositions and, more particularly, to a therapeutic composition for alleviating psoriasis. The invention is based on my discovery, that antihistaminic compounds and diuretic compounds, when used in conjunction with each other, are capable of therapeutically alleviating psoriasis when a composition containing both compounds is internally administered to a person afflicted with the disease. I have found in all instances that the use of either compound alone has virtually no effect on the course of the disease, the combined use of an antihistaminic compound and a diuretic compound exerts a unique antipsoriatic effect when both compounds are internally administered together to a psoriatic.

Psoriasis is a chronic inflammatory skin disease characterized by the development of reddish patches covered with silvery-white imbricated scales. The disease especially affects the extensor surfaces of the body and the scalp. However, the etiology and pathogenesis of psoriasis have remained somewhat obscure, and consequently no rational basis for the treatment of the disease has been evolved.

By administering standard dosages of an antihistaminic and a diuretic at the same time, I have found that both compounds are capable of exerting a unique antipsoriatic effect when used in combination, although the use of either compound by itself has no apparent effect on the course of the disease. When a composition containing both an antihistaminic compound and a diuretic compound is administered to a psoriatic patient either by injection (intramuscularly) or orally, the psoriatic lesions either disappear completely or undergo a marked diminution in size and intensity.

Accordingly, the therapeutic composition of the invention comprises an antihistaminic compound and a diuretic compound, each in amounts sufficient to cause a physiological reaction. This composition may be prepared in the form of an injectable solution for administration intramuscularly, or it may be compounded into a tablet for oral administration, the dosage in each case depending upon the particular antihistaminic and diuretic employed.

Any antihistaminic compound or any compound which functions pharmacologically as a histamine antagonist may be used in conjunction with a diuretic to prepare the antipsoriatic composition of the invention, selection of a suitable antihistaminic compound being limited solely by availability. Particularly satisfactory results may be obtained by using such commercially available antihistaminic compounds as antazoline hydrochloride, bromodiphenhydramine hydrochloride, buclizine hydrochloride, chlorcyclizine hydrochloride, chlorothen citrate, chlorpheniramine maleate, cyclizine hydrochloride, cyclizine lactate, dimenhydrinate, diphenhydramine hydrochloride, diphenylpyraline hydrochloride, doxylamine succinate, doxylamine succinate, isothiopendyl hydrochloride, meclizine hydrochloride, methafurylene fumarate, methalatal, methaphenylene hydrochloride, methapyrilene hydrochloride, methylaminophenylthienylpiperidine tartrate, parabromdylamine maleate, paracarbinoxamine maleate, phenindamine tartrate, pheniramine maleate, phenyltoloxamine dihydrogen citrate and sulfate, phenyltoloxa-

2

mine resin complex, promethazine hydrochloride, pyrathizine hydrochloride, pyrilamine maleate, pyrrobutamine phosphate, thenyldiamine hydrochloride, thonzylamine hydrochloride and tripeennamine hydrochloride.

5 When employed in conjunction with a diuretic, the dosage of these antihistaminic compounds is generally that recommended by the United States Pharmacopoeia as being the average adult dosage, although in some instances up to four times the normal dosage may be employed. The 10 minimum dosage, of course, need only be an amount sufficient to cause a physiological reaction, which will vary amongst different individuals.

The antihistaminic compound is employed in the therapeutic composition with a diuretic compound. My experiments indicate that any diuretic compound effectively cooperates to some degree with an antihistaminic compound for therapeutically alleviating psoriasis, though some diuretic compounds, notably the organomercurial diuretics as well as chlorothiazide and its derivatives, are 20 more effective than others. Satisfactory diuretic compounds for use in the antipsoriatic composition of the invention include such commercially available diuretic compounds as acetazoleamide, aminometradine, aminophylline, amisometradine, ammonium chloride, carbacylamine resin, carboxylic resins, chlormerodrin, chlorothiazide, choline theophyllinate, hydrochlorothiazide, magnesium theophyllinate, meralluride, mercaptomerin, mercurmatilin, mercurital, mercurophylline, merethoxyl-line procaine, mersalyl and theophylline, styrone resins, 30 theobromine, theophylline, theophylline isopropanolamine, theophylline methylglucamine, theophylline monoethanolamine, theophylline sodium glycinate, and urea. As in the case of the antihistaminics, the minimum dosage of these diuretic compounds is that amount sufficient to 35 cause a physiological reaction, although the normal dosage will be that recommended for the particular diuretic compound in the United States Pharmacopoeia.

Both the antihistaminic compound and the diuretic compound may be prepared in the form of an injectable 40 solution, using water or some other pharmacologically acceptable solvent, or they may be compounded into a tablet for oral ingestion, depending upon the mode of therapy selected by the physician. The frequency of 45 therapy, of course, will depend upon the individual tolerances of the psoriatic patient undergoing treatment, but as a general rule, the response of each patient will be directly proportional to the number of times the composition is administered rather than the time interval in which treatment is given.

50 Upon administration of the therapeutic composition of the invention to a psoriatic patient, there generally is a disappearance or marked diminution of itching within a 48-hour period. Continued treatment generally results in diminished scaling within the week, and the lesions

55 gradually begin to lose their inflamed character, to become salmon-pink in color, and to lose their characteristic induration. Prolonged treatment, generally lasting for five weeks or more, results in the appearance of islets of normal skin in the central or peripheral portions of

60 the psoriaformed area. These islets of normal skin gradually merge together as the lesions become lighter in color and eventually disappear altogether.

Table I sets forth the results of a series of clinical tests in which a number of psoriatic patients were parenterally treated with the antipsoriatic composition of the invention. The severity of the disease in each of these patients varied from a minimal localized eruption (Class

I), to small scattered eruptions (Class II), to moderately severe eruptions in which the lesions were discreet but generalized (Class III), and finally to diffuse generalized eruptions (Class IV). Each patient received an intramuscular injection at least once every other day. The dosage for the first five injections contained 20 mg. of chlorpheniramine maleate, 100 mg. of mersalyl, and 50 mg. of theophyllin, which was doubled after the fifth injection. The percentage improvement in each case, which was measured by a complete disappearance (corresponding to 100 percent) or a corresponding diminution in the intensity of the lesions is tabulated in Table I.

TABLE I
Treatment of psoriasis

No.	Case	Sex	Age	Duration of Disease Prior to Treatment (years)	Severity	Number of Weeks of Treatment	Number of Injections	Percent Improvement

16 months.

Although each of the foregoing clinical tests have demonstrated the results obtained when a psoriatic patient undergoes parenteral treatment using the antipsoriatic composition, comparable results may be attained by administering the composition orally.

I claim:

1. The method of alleviating psoriasis which comprises internally administering to a psoriatic patient a therapeutic composition comprising an antihistaminic compound and a diuretic compound in an amount sufficient to cause a physiological reaction until the psoriatic lesions diminish.

2. The method of alleviating psoriasis which comprises internally administering to a psoriatic patient a therapeutic composition comprising an antihistaminic compound and a diuretic compound in an amount sufficient to cause a physiological reaction until the psoriatic lesions diminish, said antihistaminic compound being selected from the group consisting of antazoline hydrochloride, bromodiphenhydramine hydrochloride, buclizine hydrochloride, chlorcyclizine, hydrochloride, chlorothen citrate, chlorpheniramine maleate, cyclizine hydrochloride, cyclizine lactate, dimenhydrinate, diphenhydramine hydrochloride, diphenylpyraline hydrochloride, doxylamine succinate, doxylamine succinate, isothipendyl hydrochloride, meclizine hydrochloride, methafurylene fumarate, methallatal, methaphenilene hydrochloride, methapyrilene hydrochloride, methylaminophenylpiperidine tartrate, parabromdylamine maleate, paracarbinoxamine maleate, phenyltoloxamine dihydrogen citrate and sulfate, phenyltoloxamine resin complex, promethazine hydrochloride, pyrathazine hydrochloride, pyrilamine maleate, pyrobutamine phosphate, thenyldiamine hydrochloride, thonzylamine hydrochloride, and tripelannamine hydro-

chloride, and said diuretic compound being selected from the group consisting of acetazolamide, aminometradine, aminophylline, amisometradine, ammonium chloride, carbacylamine resin, carboxylic resins, chlormerodrin, chlorothiazide, choline theophyllinate, hydrochlorothiazide, magnesium theophyllinate, meralluride, mercapto-merceratinerin mercurmatilin, mercurital, mercurophylline, merethoxylidine procaine, mersalyl and theophylline, styrone resins, theobromine, theophylline, theophylline isopropanolamine, theophylline methylglucamine, theophylline monoethanolamine, theophylline sodium glycinate, and urea.

3. The method of alleviating psoriasis according to claim 2, in which the diuretic compound is chlorothiazide.
4. The method of alleviating psoriasis according to claim 2, in which the diuretic compound is hydrochlorothiazide.
5. The method of alleviating psoriasis which comprises administering to a psoriatic patient an intramuscular injection of a therapeutic composition comprising about 20 mg of chlorpheniramine maleate, and about 150 mg. of meralluride until the psoriatic lesions diminish.
6. The method of alleviating psoriasis which comprises internally administering to a psoriatic patient a therapeutic composition comprising about 20 mg. of chlorpheniramine maleate, and about 150 mg. of meralluride until the psoriatic lesions diminish.
7. The method of alleviating psoriasis which comprises internally administering to a psoriatic patient a therapeutic composition comprising an antihistaminic compound and meralluride in amounts sufficient to cause a physiological reaction until the psoriatic lesions diminish, said antihistaminic compound being selected from the group consisting of antazoline hydrochloride, bromodiphenhydramine hydrochloride, buclizine hydrochloride, chlorcyclizine hydrochloride, chlorothen citrate, chlorpheniramine maleate, cyclizine hydrochloride, cyclizine lactate, dimenhydrinate, diphenhydramine hydrochloride, diphenylpyraline hydrochloride, doxylamine succinate, doxylamine succinate, isothipendyl hydrochloride, meclizine hydrochloride, methafurylene fumarate, methallatal, methaphenilene hydrochloride, methapyrilene hydrochloride, methylaminophenylpiperidine tartrate, parabromdylamine maleate, paracarbinoxamine maleate, phenyltoloxamine dihydrogen citrate and sulfate, phenyltoloxamine resin complex, promethazine hydrochloride, pyrathazine

hydrochloride, pyrilamine maleate, pyrrobutamine phosphate, thenyldiamine hydrochloride, thonzylamine hydrochloride, and tripelannamine hydrochloride.
